UNITED STATES PATENT OFFICE

JOSEPH WILLIAM GUIMONT, OF LACHINE, QUEBEC, CANADA

RADIATOR

Application filed March 23, 1931, Serial No. 524,654, and in Canada March 25, 1931.

This invention relates to improvements in radiators of the wall type used in heating buildings by means of steam or hot water and is an improvement to my application filed on the 7th day of July, 1930, in the United States of America, bearing Serial No. 465,902.

The main object of the invention is to provide an improved form of radiator particularly applicable directly upon a wall or concealed in a suitable recess in a wall, which may be covered by a panel or otherwise. Another object is to provide a radiator of attractive appearance which is easily made and cheap of manufacture.

This radiator carries approximately the same features as covered in my application above referred to, in as much as it improves the air circulation in the rooms and thus assures a lower ceiling temperature. It also occupies approximately 20% less space than an ordinary radiator of this type.

In the present invention, a novel form of radiator is produced, which provides for heating by radiation and by convection currents of air. It also provides a very large radiation surface in proportion to the space it occupies, compared with other radiators of the wall type.

In the present instance, the radiator may be simply secured to a wall in the ordinary way or may be secured in a suitable recess in a wall and conveniently concealed, provided sufficient space is allowed at bottom and top, for the air to circulate through the sections. If this radiator is secured upon the surface of a wall, the wall will not be soiled, as is the case in other types of radiators, and this is due to the fact that the exit of the air currents being below the annular flanges they are directed laterally from the radiator and not vertically.

The present invention consists in the provision of a flue between the risers of the radiator, said flue being open laterally

throughout its length as well as at the bottom and top. The flue at the bottom and top has a larger cross-sectional dimension than the flue passing through the risers, without any increase in the size of the risers. The rear of the risers are provided with a relatively wide vertical straight column with a flat back wall or surface, which has for object to partially close the flue in the rear. Thus, a free circulation of a large amount of sufficiently heated air is obtained and more efficient results are effected.

Furthermore, the present invention contemplates the provision on each section of relatively straight flat rear surfaces, slightly spaced from one another, which have the effect of enhancing the appearance of the radiator, should it be more convenient to place the radiator with its front part against the wall.

In the accompanying drawings, is illustrated one preferred embodiment of the invention:—

Figure 1 is a side elevation of a radiator section formed to provide, in conjunction with the adjoining sections, the flues and general details of construction which are peculiar to the invention.

Figure 2 is a front edge elevation of two adjoining radiator sections formed as shown in Figure 1;

Figure 3 is a rear edge elevation of Figure 2;

Figure 4 is a horizontal sectional view of two adjoining radiator sections, on line 4—4 of Figs. 1 or 2; and

Figure 5 is a top view of two adjoining radiator sections.

Referring to the drawings, 11 designates any suitable number of similar sections connected side by side to form a radiator, each of said sections including one riser 12 having at bottom and top the header portions 13, having on each side the annular flanges 14 surrounding the flow openings 15 and pro-

viding for connection of the sections by means of nipples (not shown) in the usual manner. The sections illustrated are of the form used for heating by hot water, and it should be understood that, in radiators designed for heating by steam, the upper necks and flow openings may be omitted.

The riser is formed on each side with a longitudinally extending groove 16 formed by the inward deflection of the riser walls from the vertical planes 17 between which the riser lies. These grooves are preferably nearer to the back or inner edge of the riser. The cross-sectional form of these grooves is substantially V-shaped with the inner wall 18 lying at an angle of about 90° to the plane 17, and the outer wall 19 lying at approximately 90° to the inner wall. The portions 20 of the riser wall lie outwardly of the grooves and converge toward the outer edges of the sections, as is clearly shown in Figure 4.

Inwardly of the grooves 16, the riser walls extend from one annular flange 14 to the other, as shown in the drawings and the back surface 19^a of said riser is flat from top to bottom, except for a longitudinal rib 20^a, which may be provided to enhance the appearance of the section.

30 The side walls 21 of the header portions 13 of each section are preferably flat and are located somewhat inwardly of the planes 17 and outwardly of the bottoms of the grooves 16, as shown in Figure 4.

35 It must be noted that the flanges 14 extend slightly beyond the side planes 17 of the risers so that, when two or more sections are connected together, the flanges 14 serve to space each section from the adjoining sections, and when the sections are connected together, the grooves 16 of adjoining sections combine to form one flue 22 extending from the bottom headers to the top headers. Owing to the spacing of each section from adjoining sections, narrow passages 23 are formed between the riser of each section communicating with the flues throughout their lengths, permitting air to flow laterally into or out of the flues at all points in their lengths. Passages 25, owing to the disposition of the header walls 21, inwardly of the planes 17, are formed slightly wider than the passage 23 and communicate with the lower and upper ends of the flue 22, respectively.

When a heating fluid is supplied to the radiator, air in contact with the walls thereof is heated and rises, initiating convection currents which draw cool air into the lower portion of the radiator. The cool air is drawn into the lower part of the flue 22, principally through the passage 25. As the air in the flues is heated and rises, it also expands and, because of the passages 23 and 24, the expanded air may escape laterally from the

upper portions of the flue 22, but as the upper annular flanges 14 are located immediately above said flue 22, the air current will normally be directed laterally into the room, thus protecting the walls of the room from being soiled. Naturally, the annular flange should be at such a distance from the flue, so as to not hinder the free circulation of the air through said flue. Further, it will be noted that the inner wall 18 of rear surface 19^a of the riser practically closes the rear of the sections, and α tends to direct the air circulation to the front of the flue or through the upper passage 25. More so, if the radiator is partially incased in a wall.

What I claim as my invention is:

1. A radiator comprising a plurality of similar connected sections, each of said sections including a riser portion and header portions at opposite ends of the riser portion, annular flanges projecting from opposite sides of the header portions and adapted for the connection of the sections in spaced relation, said riser being formed in opposite sides thereof with grooves extending between the headers and combining to form flues between the sections, the header portions of adjoining sections being spaced apart and thereby providing ingress and egress passages communicating with the ends of the flues formed by said grooves, the inner wall of each of said grooves extending longitudinally from one end to the other end of each of said sections connecting said upper and lower annular flanges together to form a rear wall to said header portions.

2. A radiator comprising a plurality of similar sections, including a riser and upper and lower headers connecting the upper and lower ends respectively of said riser, said riser having grooves in opposite sides thereof extending between the upper and lower headers, the grooves of adjoining sections combining to form flues through which air may flow upwardly, the inner walls of each of said grooves extending longitudinally from one end to the other end of said section, said inner wall being located closer to the inner or rear edge of the riser than to the outer edge thereof, said wall serving to divide the riser into an inner column and a larger outer column, and a rear longitudinal flat wall extending from the lower portion of said section to its upper portion constituting a back portion of uniform size throughout the whole length of said section.

3. A radiator comprising a plurality of similar sections including a riser and upper and lower headers connecting the upper and lower ends respectively of said riser, annular flanges projecting centrally from opposite ends of the header portions and adapted for the connection of the sections in spaced relation, said riser having grooves in opposite sides thereof extending between the upper

and lower headers, the grooves of the adjoining sections combining to form flues which lie in alinement with said annular flanges whereby the air currents flow upwardly in said flues and are directed laterally by means of said annular flanges through said upper headers, the inner walls of each of said grooves extending longitudinally from one end to the other end of said section thus closing the rear of said header portions.

10 In testimony whereof I affix my signature.
JOSEPH WILLIAM GUIMONT.
